UNITED STATES PATENT OFFICE.

EDWIN A. NEWMAN, OF WASHINGTON, DISTRICT OF COLUMBIA, ASSIGNOR
OF ONE-HALF TO DAVID L. SNEDIKER, OF EMPORIA, KANSAS.

VEHICLE-SHAFT COUPLING.

SPECIFICATION forming part of Letters Patent No. 411,673, dated September 24, 1889.

Application filed November 28, 1888. Serial No. 292,145. (No model.)

To all whom it may concern:

Be it known that I, EDWIN A. NEWMAN, a citizen of the United States, residing in Washington, District of Columbia, have invented 5 certain new and useful Improvements in Shaft-Couplings, of which the following is a specification.

The object of my invention is to provide improved means for attaching the shafts of 10 vehicles to the axle or vehicle-body. Heretofore shafts have usually been attached to the axle by means of pivot-bolts, which pass through lugs projecting forwardly from the axle and between which the inner ends of the 15 shafts are secured. The pivot-bolts are provided with nuts which hold them in position in the lugs. To remove the shafts it is necessary to unscrew the nuts and withdraw the bolts. This takes time and often requires a 20 special tool to unlock the nut. Besides there is a liability of the bolts and nuts being lost when removed from their accustomed position.

My invention consists in so attaching the shafts to the axle that they may be readily 25 removed therefrom without disconnecting any of the securing devices, and by which they are automatically locked in place as soon as inserted.

My invention also consists in certain details 30 of construction and organizations of instrumentalities which will be hereinafter described.

In the accompanying drawings, Figure 1 is a top view of my improved thill-coupling. 35 Fig. 2 is a vertical section with the shafts in elevation, showing, also, by dotted lines different positions of the shafts. Fig. 3 is a detail view of the strip.

I will describe my invention as applied to 40 one side of the shafts. The other side is of course applied in a similar way. The axle B is seated in a clip A, which is provided with ribs a', projecting from the bottom and terminating in screw-threaded bolts which receive nuts b. Between the nuts and the bottom of the clip is interposed a plate C, which is pressed tightly against the bottom of the axle. At its front end the plate is prolonged, and is provided with an upturned flange c', 45 which embraces the lower front edge of a gum cushion D, that is seated in a socket in the

front wall of the clip. This socket is formed by an overhanging flange d, projecting forwardly from the top of the clip. The front end of the flange is formed with an inturned 55 edge d', which fits closely the upper edge of the cushion and holds it in place. The clip is provided with side pieces E, which project forwardly from the axle beyond the cushion D. These side pieces are cut away on their 60 inner sides, as shown, to form open bearings S for the pivot-pin F of the shafts G. The front edge of the cut-away portion or recess is preferably rounded off gradually at t', as shown, to permit of the shafts being easily 65 removed and replaced. The shaft G is provided with a pivot-pin F, projecting equally from each side of the inner end. The pin F normally lies in the bearings S. The inner end of the shaft is prolonged and rounded off 70 at t to fit the concave recess e in the gum cushion D, which serves to keep the shaft from rattling, and also holds the shaft and keeps it from being taken out until turned to the position G', as indicated by dotted lines 75 in Fig. 2. When thus turned, (the strap M being out of the way,) the end t is withdrawn from the recess e, and the shafts with the pin F may be lifted out through the top of the coupling. The shafts may be turned to the 80 position shown by dotted lines G² in Fig. 2; but it cannot be lifted out of the couplings, as its end t would strike against the edge D'. It will thus be seen that the shafts are normally in good working position and can only 85 be removed when they are held up, as indicated at G'; but they are readily elevated to this position and easily removed when it is so desired.

M indicates a strap having an enlarged end 90 m, adapted to cover the opening in the coupling over the ends of the shaft and containing a weight h, the weight h serving to hold the strap in position over the shaft and prevent its bending up and exposing the interior 95 to the accumulation of dirt, water, &c. The strap passes along the top of the clip under a rib f, then over and down between the ribs a a', under the axle, over a transverse bar f', extending from the bottom of one side piece 100 E to the other, and its outer end is finally connected by means of an eye o to a hook n

on the under side of the shaft G. By this construction, when the shafts are down the end *m* of the strap covers the end of the shaft; but in the act of elevating the shaft the end 5 *m* is drawn out of the way, allowing the shafts to be withdrawn from the bearings. The construction also prevents the shafts being turned too far over when elevated, as the enlarged weighted end *m* comes in contact with the 10 rib *f*. The strap serves principally, however, as a safety device.

The construction shown is simple and efficient; but certain details of construction may be varied without departing from my invention, 15 my main object being to provide a shaft-coupling wherein the shafts are secured, held in place when in working position, but can be readily removed and replaced.

I claim as my invention—

20 1. The combination, substantially as hereinbefore set forth, of the clip, the forwardly-projecting side pieces, the shafts, the cylindrical pivots resting in open bearings in the side pieces, the removable bottom plate of the 25 clip, the overhanging top flange *d*, projecting

beyond the rearwardly-projecting end of the shafts, the cushion *D*, seated in a socket in the front wall of the clip, said cushion being formed with a concave recess *e*, into which the end of the shafts extend.

2. The combination, substantially as hereinbefore set forth, of the shafts, the open bearings therefor, the strap at one end covering the bearings and secured at its opposite end to the shafts, so that when the shafts are 30 elevated the strip is removed from the bearings.

3. The combination, substantially as hereinbefore set forth, of the shafts, the clips, the forwardly-projecting side pieces, the open 40 bearings therein, the strap enlarged and weighted at one end and secured at its opposite end to the shafts, and the guides for the strip.

In testimony whereof I have hereunto subscribed my name.

EDWIN A. NEWMAN.
